AIR CONDITIONING SYSTEM UTILIZING
REFRIGERATIONSamuel M. Anderson, Sharon, Mass., assignor to
B. F. Sturtevant Company, Inc., Boston, Mass.

Application March 13, 1936, Serial No. 68,698

3 Claims. (Cl. 62—6)

This invention relates to air conditioning systems utilizing refrigeration and relates more particularly to an air conditioning system for passenger vehicles, combining evaporative cooling with cooling by refrigeration.

The passenger cars on some railroad lines on one continuous trip, pass through regions in which, in summer, different demands are made upon the air conditioning equipment. For example, a train may first pass through a region having a high wet bulb as well as a high dry bulb temperature, requiring considerable refrigerating energy for the cooling and dehumidification of the air. The train may next pass through a region having such a low wet bulb temperature that evaporative cooling may be effectively employed. Then at night, a sufficient cooling effect may be secured by forcing an increased volume of outside air through the car.

According to this invention, a spray cooling system is supplied with refrigeration when conditions require such; is operated in evaporative cooling when effective, and when effective, the sprays are discontinued and the cooling effect is secured by the circulation of an increased volume of outside air. Indicators are provided for indicating changes in conditions enabling changes in the operation of the conditioner, and controls are provided for changing the method of operation of the conditioner and for maintaining the desired indoor conditions, with a minimum of equipment and without operating difficulties.

An object of the invention is to provide means and methods for effective air conditioning with and without refrigeration.

Another object of the invention is to provide a switching arrangement with indicators and controls for the effective conditioning of air utilizing refrigeration when needed and dispensing with refrigeration when not needed.

Other objects of the invention will be apparent from the following description taken together with the drawings.

The invention will now be described with reference to the drawings of which:

Fig. 1 is a diagrammatic view of the invention as applied to a railroad passenger car;

Fig. 2 is a side sectional view of a railroad passenger car equipped according to this invention;

Fig. 3 is a plan view in section of the car of Fig. 2; and

Fig. 4 is a cross-sectional view of the car.

The system illustrated was designed for a particular railroad line extending across a particu-

lar section of North America. The design was based upon the knowledge that during one period of travel the maximum outdoor temperatures to be expected were 95° dry bulb and 72° wet bulb. With such temperatures, it was determined that a sleeping car with 50 passengers could be maintained comfortable at a 77° dry bulb temperature and 62% relative humidity by the circulation of 2220 cubic feet per minute of 40% outdoor air and 60% recirculated air cooled by passage through water sprays chilled by an ice melting at a rate of 5 tons per 24 hours, in an ice chamber.

During another period of travel the outdoor dry bulb temperature remains at 95° but the outdoor wet bulb temperature decreases to 61°. This permits evaporative cooling; the spray water is by-passed around the ice chamber, and all outside air passes through the conditioner. The spray conditioner is so designed that the recirculated spray water is chilled by evaporative cooling to 61° and the air leaving the conditioner will be cooled to about 62°. The discharge of this air into the car maintains the desired standard of 77° and 62% relative humidity.

During another period of travel the outdoor temperature at times as at night, drops to 72.8° dry bulb with 68.1° wet bulb. At such time, the sprays are discontinued and the fan system is converted to force 4,000 cubic feet per minute of outside air through the car. This maintains the car at 76° dry bulb and even though the relative humidity may rise as high as 76% inside the car, the effective temperature which is a measure of human comfort, is unchanged, and the air is comfortable.

A control panel is provided with four positions marked as "High", "Medium", "Medium low", and "Low". When the controls are switched by a train attendant to "High", a temperature of 76° dry bulb is maintained in the car by the passage of 4,000 cubic feet of outside air, without temperature conditioning, through the car. A red light on the panel lights when the outdoor dry bulb temperature drops below 73° which is low enough for this cooling by ventilation to be sufficient. A car thermostat adjusts the air volume when the indoor temperature drops too low.

When the outdoor temperature is above 73° F. dry bulb and at or below 61° wet bulb, the red light on the panel goes out and a white light appears. This indicates that ventilation alone is no longer sufficient and that evaporative cooling is required. The train attendant then switches the controls to provide the evaporative cooling of

2,220 cubic feet per minute of outdoor air. A car thermostat controls the volume of spray water.

When the outdoor wet bulb rises above 61° with outdoor dry bulb above 73°, a blue light will appear in the panel with the red light out. This is a signal to the train attendant that cooling by refrigeration is required and he switches the controls to accomplish this and to pass recirculated air through the conditioner. A car thermostat regulates the spray water.

With the blue light still on the panel, another adjustment is provided for satisfying possible passenger complaints that the air is too cold. The porter then switches the controls to decrease the volume of air passing through the conditioner, to 1350 cubic feet per minute.

As the outdoor temperature decreases, the train attendant is warned, of course, by the lights on the panel to switch the controls towards the "High" position. When, however, the outdoor temperature has dropped to a point where with the controls at "High", the passenger space is too cold, the train attendant shuts down the cooling apparatus and operates the ordinary heat control (not shown) to supply heat to the car.

The operation of the conditioner and of the controls will now be described with reference to Fig. 1 of the drawings.

The conditioner 6 located in the upper portion 30 of the right hand end (facing the drawing) of the car is provided with the spray nozzles 7, the fans 8, the outside air inlet 10, the recirculated air inlet 11, and the air discharge outlet 12. The fans 8 are driven by the motor 13 energized by the battery 14. A filter is provided in the inlet 10. The ice chamber 15 supplies ice water to the spray nozzles 7, through the intermediary of the pipe 16; pump 17 and pipe 18. The water collected from the sprays in the conditioner 6 is returned through the pipe 19, to the ice chamber 15 for recooling.

At the opposite end of the car from the conditioner 6 is arranged the blowers 20, driven by the motor 21 which is connected in parallel to the motor 13 for the conditioner 6. The blowers 20 handle all outside air drawn in through the inlet 22 which like the outside air inlet 10 is provided with a filter. The outside air leaving the blowers 20 passes through the outlet 23 into the passenger space.

When the outdoor wet bulb temperature is above 61° F., the wet bulb thermostat 24 mounted in the outside air passage 25, closes a circuit including the wire 26, battery 14, the wire 27, the contacts 28, the arm 29, the filaments of the blue lights 30 and 31, the wire 32 and the wire 33. This causes the lights 30 and 31 to glow, indicating to the train attendant that the switch arm 34 should be moved to a position in line with the light 31. When this is done, the resistor contact 35 moves against the point 37 on the resistor 36, in circuit with the blower driving motors 13 and 21, placing sufficient of the resistor 36 in the circuit of those motors to enable them to operate at a speed to provide 2220 cubic feet of air per minute. The energizing circuits of the motors 13 and 31 include the battery 14, the wire 38, the switch arm 34, the contact 35, the resistor 36 at point 37, the switch 39, the wires 40 and 41 and the motor buses 42 to the motors 13 and 21.

The switch arm 34 provides for the supply of refrigeration by closing a circuit including the motor 43 driving the pump 17, the wire 44, the battery 14, the wire 38, the arm 34, the segment

46, and the wire 47. The pump then operates to supply water to the spray nozzles 7.

In order to ensure that the water supplied at this time to the nozzles 7 is ice water, the switch arm 34 closes a circuit including the solenoid 48, the wire 49, the battery 14, the wire 38, the arm 34, the segment 50 and the wire 51. This energizes the solenoid 48 to adjust the valve 52 to close off the by-pass pipe 53 around the ice chamber 15, and to open the pipe 54 to the spray nozzles in the ice chamber.

The mercury type thermostat 55 acts to maintain the desired dry bulb temperature of 77° in the car by controlling through the control valve 56, the volume of refrigerated water supplied to the sprays in the conditioner 6. When the temperature in the car is at or above 77°, a circuit including the thermostat 55, the wire 57, the solenoid 58, the wire 59, the battery 14, and the wire 49 is closed. This energizes the solenoid to hold open the valve 56. When the temperature falls below 77°, this circuit is opened, the solenoid 58 is deenergized and the valve 56 is partially closed to decrease the volume of water supplied to the spray nozzles 7.

If the passengers complain that the air is too cold, the train attendant by moving the switch arm 34 in line with the blue light 30, reduces the air volume to 1330 cubic feet per minute, the other apparatus functioning as before. Due to the decreased air volume, the temperature should rise to 78°. If the temperature rises above 78°, the car thermostat 55 automatically adjusts the valve 60 to provide an increased water volume to the spray nozzles 7. This is accomplished by the thermostat 55 closing a circuit including the wire 61, the solenoid 62, the wire 63, the contact 64, the switch arm 34, the wire 38, the battery 14 and the wire 49. The solenoid 62 is thus energized to open completely the formerly partially closed valve 60. When the temperature falls again to 78°, this circuit is opened and the valve 60 is partially closed.

When the outdoor wet bulb temperature drops to 61° F., the wet bulb thermostat 24 opens the above described circuit including the blue lamps 30 and 31, and the wet bulb thermostat 64 closes a circuit including the wire 65, the relay 45, the battery 14, the wire 27, the contacts 66, the switch 67, the wire 68, the white lamp 69, and the wire 70. The resulting lighting of the white lamp 69 indicates to the train attendant that outdoor conditions are such that cooling by evaporation may suffice. He then moves the switch arm 34 in line with the lamp 69, to the position marked "Medium".

In the meantime, the relay 45 has been energized to close a circuit including the wire 71, the wire 59, the battery 14, the wire 72, the upper wire 42, the damper control motor 73 and the wire 74. This energizes the motor 73 causing it to close the dampers 75 in the recirculated air inlet 11, thus providing that all outside air passes through the conditioner.

When the switch arm 34 is moved to "Medium" position, the above described circuit including the segment 50 and the solenoid 48 is opened, causing the solenoid to become deenergized and to adjust the valve 52 to close off the pipe 54 in the ice chamber 15 and to open the by-pass pipe 53, this causing the water returned from the spray nozzles 7 to by-pass the ice chamber 15, so that cooling is effected by evaporative cooling. The fan speed remains unchanged due to the same value of the resistor remaining in 75

the fan motor circuit. The car thermostat 55 maintains the car temperature at 77° during this period of evaporative cooling by control of the water throttling valve 56 as previously described.

5 When the outdoor dry bulb temperature drops to 72.8° F., the thermostat 16 closes a circuit including the wire 17, the wire 65, the relay 45, the battery 14, the wire 27, the solenoid 78, the wire 79, the red lamp 81, and the wire 80. This causes 10 as described in the immediate foregoing, the relay 45 to energize the damper control motor 73 to close the recirculated air dampers. It also causes

the thermostat 55 from controlling the blower speed except when the switch arm 34 is at "High".

The solenoid 78 which is energized when the red light is on, opens the circuits of the blue lamps 30 and 31 by moving the arm away from the contacts 28, and the arm 67 away from the contacts 66. This prevents the blue lights from glowing at the time that the red light is on.

The following tabulation illustrates at a glance, 10 the practical operation of the apparatus described in detail in the foregoing:

15 Outside temperature	72.8 deg. D. B. 68.1 deg. W. B.	95 deg. D. B. 61 deg. W. B.	95 deg. D. B. 72 deg. W. B.	15
Control set	High	Medium	Medium low	
Car temp. maintained inside	76 deg. D. B. 70 deg. W. B. 73 deg. E. T. 76% R. H.	77 deg. D. B. 68 deg. W. B. 73 deg. E. T. 62% R. H.	77 deg. D. B. 68 deg. W. B. 73 deg. E. T. 62% R. H.	
Car thermostat	Regulates air	Regulates spray	Regulates spray	
20 Total air	4,000 c. f. m.	2,220 c. f. m.	2,220 c. f. m.	20
Outside air	100%	100%	40%	
Recirculated	6%	0%	60%	
Fans running	4	4	4	
Appx. fan. H. P.	1/4 H. P.	1/4 H. P.	1/4 H. P.	
Electric pump	Off	On	On	
Gals. per min.	0 G. P. M.	19 G. P. M.	13 G. P. M.	
Water temp.		61 deg. F.	40 deg. F.	
Ice bin cooling	Off	Off	On	
25 Appx. pump H. P.	0	1/4 H. P.	1/4 H. P.	25
Cooling results from	Rapid introduction of large quantities of cool outside air	Evaporation of spray water into dry outside air	Cold iced spray water in contact with recirc. and outside air	
Telltale light indicator	Red lights when outside D. B. thermostat indicates a dry bulb temp. below 73° F.	White lights when outside W. B. thermostat indicates a wet bulb temp. at or below 61 deg. F.	Blue lights when outside W. B. thermostat indicates a wet bulb temp. above 61 deg. F.	30

When red light is on neither white nor blue car light because of interlocking controls.

Control instructions to porter	1. Turn to "High" when red light is on. 2. Turn to "Medium" when white light is on. 3. Turn to "Med. Low" when blue light is on. 4. Turn to "Low" when blue light is on only to satisfy passenger complaints.	35

the red lamp 81 to glow, indicating to the train attendant that sufficient cooling may be supplied by discontinuing the sprays and by increasing the outside air volume. He then moves the switch arm 34 in line with the red lamp 81, to "High" position. The arm 34 leaves the segment 46 causing the above described circuit including the pump motor 43 to be broken, thus shutting down the pump 17, and the supply of water to the sprays. The contact 35 moves with the switch arm 34 to remove all of the resistance 36 from the circuit of the blower driving motors 13 and 21, causing these motors to rotate at an increased speed to cause the blowers 8 and 20 to force 4,000 cubic feet per minute of outside air through the car.

With the switch arm 34 at "High" position, the car thermostat 55 controls the car temperature by varying the blower speed from a rate of 4,000 cubic feet of air per minute to a rate of 3,000 cubic feet of air per minute. When the temperature within the passenger space drops below 76°, the thermostat 55 acts to open a shunt across the resistor 85, placing it in series with the current supply to the blower driving motors to reduce their speed. Normally, the temperature is above 76° with the result that a circuit including the thermostat 55, the solenoid 86 and a battery is closed, causing the solenoid 86 to hold its switch arm 87 against the contact 88, thus maintaining the resistor 85 shunted out of the blower motors energizing circuit. The contacts of the switch 39 are connected across the resistor 85, maintaining the resistor shunted out of service, except when the switch arm 34 is at "High" position, at which time the extension 89 on the contact arm 35, presses against the extension 90 of the switch 39, causing it to open. This prevents

The manually operated control panel could of course be replaced by a completely automatic control, in which case, the thermostats in the outside air passage would act to energize solenoids for closing the contacts on the control panel. The manually operated control panel is preferred because of its ease of adjustment, simplicity, and for the additional reason that the railroad line for which the system was designed, 40 prefers such an arrangement. 45

Figs. 2, 3, and 4 illustrate the preferred arrangement of the apparatus together with a novel duct system. The blowers 20 discharge into one end of the ducts 91 and the blowers 8 discharge 60 into the other end of the same ducts. This arrangement enables considerably more air to be moved through the passenger space than has been the practice in the past. The ducts 91 discharge into the passenger space through the 55 spaced overhead outlets 92 and into the lower berths through vertical ducts 93 and outlets 94.

While one embodiment of the invention has been described for the purpose of illustration, it should be understood that the invention is not limited to the exact arrangement described, since many departures will suggest themselves to those skilled in the art, after having had access to this disclosure.

What is claimed is:

1. Air conditioning apparatus for a passenger vehicle comprising an air cooler, means for supplying a refrigerating fluid to said cooler, means for supplying outside air to said cooler, means for supplying air recirculated from the passenger space of said vehicle, to said cooler, means for discontinuing the supply of fluid to said cooler, for discontinuing the supply of recirculated air to said cooler, and for increasing the volume of 75

- outside air supplied to said cooler, for effecting cooling by the ventilating effect of an increased volume of outside air when its temperature is sufficiently low for such to be effective, a control panel, and controls on said panel for controlling all of said means.
2. Air conditioning control apparatus for a passenger vehicle having an air washing system adapted to operate alternatively in refrigerative cooling or evaporative cooling cycles, comprising a visual signal in said vehicle for indicating when said system should be operated in the evaporative cooling cycle, and means responsive to changes in the wet bulb temperature of outdoor air entering said system for actuating said signal when the wet bulb temperature of the outdoor air has fallen to a predetermined minimum point.
- 5
- 10
- 15

3. Air conditioning control apparatus for a passenger vehicle having an air cooling system, comprising a pair of signal lamps in said vehicle for indicating when adjustments should be made in said system, means responsive to changes in the wet bulb temperature of the outdoor air entering said system for actuating one of said lamps when the wet bulb temperature of the outdoor air has fallen to a predetermined point, and means responsive to changes in the dry bulb 10 temperature of the outdoor air entering said system for actuating the other of said lamps when the dry bulb temperature of the outdoor air has fallen to a predetermined point.
